UNITED STATES PATENT OFFICE.

ALBERT GEORGE MARRIOTT AND MERNERD JOHN MARRIOTT, OF GUELPH, ONTARIO,
CANADA.

GYMNASTIC APPARATUS.

1,115,223.

Specification of Letters Patent. Patented Oct. 27, 1914.

Application filed March 31, 1914. Serial No. 828,483.

To all whom it may concern:

Be it known that we, ALBERT G. MARRIOTT and MERNERD J. MARRIOTT, subjects of Great Britain, residing at Guelph, Province of 5 Ontario, Canada, have invented certain new and useful Improvements in Gymnastic Apparatus, of which the following is a specification.

Our invention contemplates means or apparatus for the performance, in a theater, 10 circus, or arena, of aerial gymnastic or acrobatic feats of novel, sensational, and startling character.

Generally stated, the invention embodies 15 a revoluble superstructure, which constitutes a main support or platform on which or from which gymnastic or acrobatic feats may be performed, and equipped with another revoluble element adapted for the support 20 and carriage of one or more gymnasts.

More specifically stated, the invention embodies an elevated revoluble superstructure, 25 which simulates an aeroplane, equipped with a propeller-like rotor adapted and arranged to carry a gymnast and to be given a whirling motion in a direction at substantially a right angle to the planes, and whereof the planes are adapted and arranged to support 30 or carry various quickly detachable gymnastic accessories, such as trapeze, rings, suspension devices, and other adjuncts.

The nature, characteristic features and scope of the invention will more readily be understood from the following detailed description taken in connection with the accompanying drawings forming a part hereof, wherein—

Figure 1 is a perspective view of gymnastic apparatus embodying features of our 40 invention. Fig. 2 is a perspective view with the curtain and other paraphernalia removed to expose the gearing or operating mechanism. Fig. 3 is a detail of the trigger-release mechanism.

Referring to the drawings, numeral 1 indicates a drum-like support or table sustained in elevated position by standards 2 braced and secured in any suitable manner. The drum or table 1 is provided with a 45 roller path 3, which constitutes an anti-frictional support for a second drum 4 on which is mounted the superstructure. The drum 4 is designed to be rotated in either direction and any suitable means or power may 50 be employed for this purpose, but for the

sake of illustration we show a gear wheel 5 fast on the drum and centered by a shaft 6, suitably mounted, said gear wheel meshing with a pinion 7 fast on a crank or drive shaft 8. 60

The superstructure, which in the present embodiment takes the form of a flying-machine or aeroplane, is generally indicated by the numeral 9. Its light frame-work for the planes and other structural elements is 65 principally sustained by a heavy transverse bar 10 secured as by standards 11 to the revoluble drum 4.

12 and 13 are cross-pieces on the drum 4 for supporting and bracing other elements of 70 the superstructure. For example, the cross-piece 12 may have a mast or upright 14 equipped with brackets 15 and 16 on which may be mounted a siren 17 and search light 18. The rods 19 carry the after part of the 75 aeroplane, and the guy ropes or wires 20 tend to steady the cross plane 21.

In order to further enhance the appearance of an aeroplane and also to meet the demands of the public for feats of startling 80 nature, we provide a rotor 22. This may have any form adapted for the support and carriage of one or more players or gymnasts. The device illustrated consists of a hub 23 having radial open frames 24 and 25. The 85 frame 24 is longer than the other frame so that it acts as a counterbalance. Frame 24 accommodates the lower extremities and has stirrups or foot-straps 26, and frame 25 is made large enough to admit the head. The 90 hub of the rotor is secured to a shaft 27, which is adapted and arranged to rotate in a plane at substantially a right angle to the axis of rotation of the superstructure. The rotor shaft is journaled in suitable bearings 95 28 supported by the cross-piece 13, and it may be driven in any suitable manner, for example by the bicycle gearing illustrated, wherein 29 indicates the operator's seat or saddle and its complemental frame, and 30 100 indicates a crank-shaft operated by pedals 31 and having gears 32, 32 either of which may be caused in the well-known manner to mesh with a gear 33 on the shaft 27 so as to drive the latter in one or the other direction. 105

The superstructure is equipped with various suspension devices or apparatus for use in the performance of gymnastic or acrobatic feats, for example, a trapeze 34, a strap 35 for suspension by the teeth, and 110

means for supporting and quickly releasing some part of the apparatus, for example a bicycle in such manner as to give the impression of an accident. This is provided for as follows: At one end of the bar or beam 10, there are two straps 36 and 37 whereof the former is adapted and arranged to support a bicycle and rider and whereof the strap 37 is a safety element and is intended to be secured to the rider. Strap 36 is suspended from a hook 38 having a pivotal part 39, which is normally upheld by a spring-pressed trigger 40. A cord 41 having one end attached to the trigger and the other end passed over a pulley 42 and then down within easy reach of the rider, serves to release the trigger at the climax of the act and permit the fall of the bicycle.

An elaborate shield or curtain 43 enhances the ornamental appearance of the apparatus and also conceals the support or pedestal and likewise the operating mechanism.

Manifestly all of the parts are separable or quickly detachable so that the structure may be assembled or dismantled with ease and facility.

Having described the nature and objects of the invention what we claim as new and desire to secure by Letters Patent is:—

- 30 1. Apparatus of the character described, embodying a support, an aeroplane structure mounted for rotation thereon and equipped with means for the performance of gymnastic feats including a rotor adapted for the support and carriage of a gymnast, means for rotating the aeroplane structure, and independent driving means for the rotor.
- 40 2. Apparatus of the character stated, embodying a support and an aeroplane structure mounted for rotation thereon and equipped with aerial suspension apparatus

and with a laterally projecting rotor capable of rotation in a direction at substantially a right angle to the axis of rotation 45 of the aeroplane, said rotor consisting of radial open frames equipped with holding devices.

3. Apparatus of the character stated, embodying an elevated support having a roller path, an aeroplane structure mounted for rotation thereon and equipped with means for the performance of gymnastic feats including a rotor having radial open frames adapted for the support and carriage of a 55 gymnast, and means for driving the aeroplane structure and rotor independently of one another.

4. In an aerial gymnastic apparatus, the combination of an aeroplane structure 60 equipped with means for the performance of gymnastic feats and capable of rotation on a vertical axis, means for rotating it, a motor carried by said aeroplane structure and having a shaft projecting laterally beyond the latter, and a hub on said shaft equipped with radial open frames adapted 65 and arranged to support a gymnast.

5. In an aerial gymnastic apparatus, the combination of a structure equipped with 70 means for the performance of gymnastic feats and capable of rotation on a vertical axis, means for rotating it, an auxiliary gymnastic device consisting of a balanced rotor carried by said structure, and means 75 for driving the rotor at a speed greatly in excess of that of the structure.

In testimony whereof we affix our signatures in presence of two witnesses:

ALBERT GEORGE MARRIOTT.
MERNERD JOHN MARRIOTT.

Witnesses:

J. D. YOAKLEY,
JAS. A. RICHMOND.
